UNITED STATES PATENT OFFICE.

WILLIAM A. HOUCK, OF READING, PENNSYLVANIA.

MOISTENING MEANS FOR COP MOUNTINGS.

1,419,734.

Specification of Letters Patent. Patented June 13, 1922.

Application filed April 16, 1921. Serial No. 461,759.

To all whom it may concern:

Be it known that I, WILLIAM A. HOUCK, a citizen of the United States, residing at Reading, in the county of Berks and State 5 of Pennsylvania, have invented certain new and useful Improvements in Moistening Means for Cop Mountings, of which the following is a specification.

My invention relates particularly to means 10 for moistening the thread or yarn of cops such as are employed in knitting operations, and it consists in an improved mounting comprising a liquid container located to constantly maintain adequate moistening of the 15 entire cop without in any way interfering with the usual simple manner of replacing used cops with filled ones. The invention is fully described in connection with the accompanying drawings, and the novel features 20 are pointed out in the claims.

Fig. 1 is a sectional elevation of a simple cop mounting embodying my invention.

Fig. 2 is a plan view of the winged cop support employed.

25 The desirability of properly moistening thread or yarn during its fabrication is understood, and my invention provides simple means for satisfactorily effecting such moistening particularly in cop mountings 30 such as are indicated in the accompanying drawings.

Referring to the drawings, 5 represents any suitable base plate or bracket for supporting the cop. Vertically mounted in said 35 plate 5, is a cop-support spindle 6, the upper end of which carries a cop support 7; the lower threaded end of said spindle, as shown, having a thumb nut 8 to regulate the lifting action of a spring 9 which is strung upon the 40 spindle 6 and arranged to press upon a liquid container 10 resting upon the base plate 5.

This liquid container is cup-shaped as shown and has a central inner wall 11 enclosing the spindle 6, and forming an annular water chamber 10. The cop support 7 is formed as shown with four wings 7^a, providing passage ways between them for moist air arising from the container 10. The outer edges 14 of each of these wings is inclined 50 so that the support will readily enter the usual paper cone 15 of the cop. As these paper cones are apt to be warped by moisture rising from the liquid container 10 and thereby cause binding upon support 7, I cut 55 back portions of the wings 7^a as indicated at 16, so as to permit only the upper and

lower portions of the wings to normally contact with the cone 15, but so as to still provide sufficient taper in the cut-back edges to prevent locking of a warped cone upon the 60 support.

Water or other liquid supplied to the container 10 causes moisture to rise between the wings or projections of the cop support 7 and to contact with the cone 15 of the cop, 65 thereby moistening the same and sufficiently affecting the yarn or thread wound upon the latter; apertures 17 however being provided in the cone if desired to facilitate proper moistening of the yarn. 70

From the foregoing description it will be seen that my mounting provides in a simple and effective way, for moistening the thread or yarn as is desirable in operation and to prevent possible adhesion of the same to the 75 paper cone. The cops are mounted and replaced in the usual manner by simply pushing the same down upon the cop support 7; and the reduced contact provided by the cutting back of the wings as indicated at 16 permits of warping and shrinkage of the moistened cone without danger of binding or locking. The device is applicable to old 80 mountings though particularly adapted to the improved mounting shown in my prior 85 Patent No. 1,377,416 dated May 10, 1921.

What I claim is:

1. In combination with a base plate, a winged cop support mounted thereon, and a liquid container located between said support and the base plate. 90

2. In combination with a base plate, a spindle mounted thereon and carrying a winged cop support, and a liquid container mounted upon the spindle below said support. 95

3. In combination with a base plate, a spindle mounted thereon and carrying a winged cop support, a liquid container having a central sleeve enclosing said spindle 100 below the support, and a cop-support spring upon said sleeve.

4. In combination with a base plate, a winged cop support mounted thereon, and a liquid container located between said support and the base plate; said cop-support wings being cut back intermediate of their length to normally prevent contact with the cop cone. 105

In testimony whereof I affix my signature. 110

WILLIAM A. HOUCK.
